DESIGN FOR A TREE BASE

Joseph T. Barton, Chicago, Ill.

Application October 17, 1938, Serial No. 80,512

Term of patent 3½ years

To all whom it may concern:

Be it known that I, Joseph T. Barton, a citizen of the United States, residing in Chicago, county of Cook, and State of Illinois, have invented a new, original, and ornamental Design for Tree Bases, of which the following is a specification, reference being had to the accompanying drawing, forming a part thereof.

Fig. 1 is a perspective view of a tree base showing my new design,

Fig. 2 is a perspective view, showing the two semicircular halves of the tree base in Fig. 1 separated.

I claim:

The ornamental design for a tree base, as shown and described.

JOSEPH T. BARTON.
